(57) **CLAIM**

The ornamental design for a cooling container, as shown and described.

DESCRIPTION

FIG. 1 is a top, front perspective view of a cooling container, showing my new design;

FIG. 2 is a bottom, front perspective view thereof;

FIG. 3 is a front elevation view thereof;

FIG. 4 is a right side elevation view thereof;

FIG. 5 is a rear elevation view thereof;

FIG. 6 is a left side elevation view thereof;

FIG. 7 is a top plan view thereof; and,

FIG. 8 is a bottom plan view thereof.

The cooling container is used to house a specialized gel used for extending the life and use of ice.
